Primary Examiner—Freda Nunn
Attorney, Agent, or Firm—Robert C. Kain, Jr.[57] **CLAIM**

The ornamental design for a top portion of a keyboard surface, as shown and described.

DESCRIPTION

FIG. 1 is a top plan view of a top portion of a keyboard surface showing our design;

FIG. 2 is a front side elevational view thereof;

FIG. 3 is a rear side elevational view thereof;

FIG. 4 is a left side elevational view thereof;

FIG. 5 is a right side elevational view thereof; and, FIG. 6 is a top plan view of an alternate embodiment thereof wherein the only difference is in the omission of the characters.

The shading in the top plan views is illustrative of color.
